UNITED STATES PATENT OFFICE.

GEORGE H. THACHER, JR., OF ALBANY, NEW YORK.

FEEDING DEVICE FOR FURNACE-GRATES.

1,134,167.

Specification of Letters Patent. Patented Apr. 6, 1915.

Application filed October 22, 1912. Serial No. 727,147.

To all whom it may concern:

Be it known that I, GEORGE H. THACHER, Jr., a citizen of the United States, residing at Albany, county of Albany, and State of New York, have invented certain new and useful Improvements in Feeding Devices for Furnace-Grates; and I do hereby declare the following to be a full, clear, and exact description of the invention, such as will enable others skilled in the art to which it appertains to make and use the same.

My invention relates to certain new and useful improvements in fuel-feeding devices for steam-boiler and other furnaces, and it relates particularly to that type of fuel feeders wherein the fuel is supplied from a hopper to a feed screw operating in a longitudinal trough from which the fuel is received, on both sides of the trough, upon inclined grates located at the foot of the inclines.

Prior to my present invention, it has been considered necessary, for practical purposes, that the conveyer blades of that portion of the feed screw which are located beneath the hopper be given a different and sharper pitch than the conveyer blades operating in the main body or magazine portion of the trough, and it has also been considered necessary to provide between the fuel-receiving portion of the trough and the magazine proper a cylindrical passageway, through which the fuel was forced on its way into the magazine.

My present invention is based upon the discovery that it is feasible to provide the same pitch for the conveyer blades, throughout the entire length of the screw, provided that certain provisions are made, as herein-after set forth, for facilitating the feeding operation and also for insuring the uniform raising and distribution of the fuel in the magazine. To this end, in accordance with my invention, I entirely omit the cylindrical passageway referred to, and admit the fuel from the hopper directly upon the conveyer blades of the feed screw, and provide the same pitch for the conveyer blades from

end to end of the feed screw, the arrangement being further such that the conveyer blades terminate at a suitable distance from the farther end of the magazine. By this construction and arrangement, the fuel received from the hopper upon the initial conveyer blades of the screw is fed forward

without any liability whatever of choking on its way to the magazine portion of the trough, full clearance being provided by reason of the absence of the cylindrical passageway heretofore employed. So also, by terminating the conveyer blades at a point well in advance of the rear end of the magazine portion of the trough, I am enabled to raise the fuel in the uniform manner requisite for the proper distribution thereof over the top edges of the magazine and upon the inclined grates, and without employing so-called raising blades of different and lesser pitch than the initial conveyer blades.

In the accompanying drawing, I have illustrated the preferred construction embodying my invention.

Figure 1 represents a longitudinal sectional view, partly in elevation, of my improved feeding devices, as applied to a steam boiler furnace. Fig. 2 represents a cross-sectional view thereof.

Similar letters indicate similar parts in both views.

Referring to the drawing, A indicates the front wall of the steam boiler furnace, of any suitable type, as, for instance, the water tube boiler B.

The hopper C discharges upon the initial conveyer blades of the feed screw, as shown. The feed screw consists preferably of a rotary shaft a upon which are removably splined a series of sleeves b carrying the conveyer blades c. Upon the forward end of the shaft a is mounted the worm gear d adapted to be operated by the worm e from any suitable source of power.

The feed screw operates in the bottom of the trough, and terminates within the magazine section D thereof at a point well in advance of the extreme end of the magazine section, the space beyond being occupied by the plain sleeve f as indicated in Fig. 1. The end of the magazine D is occupied by the casting E which may conveniently be set in the bridge wail F of the furnace with suitable provision for expansion of the parts.

The forward end of the trough constitutes a separate casting G and, as shown, is supported in the front wall H of the furnace, in alignment with the magazine section D. It communicates with the magazine section freely, its side walls coinciding therewith from the hopper inlet g on. Consequently,

there is no opportunity afforded for detention of the fuel or clogging thereof on its way from the hopper of the trough into the magazine. The top plate *h*, which may 5 either be integral with the casting, as shown, or which may be a separate plate, is given an upward inclination reaching from the hopper inlet to the inner wall of the brick-work *H*, so as to further facilitate the passage of the fuel into the magazine without 10 back-pressure. Should any of the conveyer blades become worn or injured, they may be replaced by substituting in their place a like sleeve section corresponding to the particular blades removed.

The magazine *D* may conveniently be made of two castings having suitable ribs and flanges as indicated more fully in Fig. 2. The magazine discharges upon the inclined grates *I*, which are supported by the hangers *J*, and the side grates themselves discharge upon the dumping grates *K*, as shown. The upper surfaces *j* of the side walls therefore serve, in a measure, as coking surfaces for the fuel, before it strikes the inclined grates themselves, and, more particularly, by reason of the extra fitting of the projections or tongues *i* with the grooves in which they are received, the penetration of air from the ash pit *L* into the fuel directly above the magazine is prevented.

Having thus described my invention what I claim is:

- 35 1. Feeding devices for inclined grate furnaces consisting of a trough unrestricted from end to end and having a hopper section and a magazine section, and a feed screw having blades of substantially equal pitch within the hopper section, and within the magazine section, said blades terminating well in advance of the rear end of the magazine, said hopper section comprising a hopper and having a flaring outlet portion 40 extending from said hopper backward to said magazine section to permit an unrestricted flow of coal into said magazine section, and into the front end of the fire box.
- 45 2. Feeding devices for furnaces consist-

ing of a trough having a hopper section and a magazine section, said magazine section being unobstructed from end to end and the side walls of said magazine and hopper sections being in alinement, said hopper section flaring upward directly from the hopper feed opening toward the magazine section, and a continuous feed screw of substantially uniform diameter operating in the bottom of the trough throughout the greater part of its length; substantially as described. 55 60

3. Feeding devices for furnaces consisting of a trough unrestricted from end to end having a hopper section and a magazine section, the side walls of said sections being in alinement, and the hopper section having 65 a coal hopper at one end, and being of increasing area from the hopper feed opening onward, until it meets the magazine section, and a feed screw of uniform pitch and diameter throughout, operating in the bottom 70 of the trough, said feed screw lying partly in said hopper section and terminating well in advance of the rear end of the magazine; substantially as described.

4. Feeding devices for inclined grate furnaces consisting of a trough located below the upper edges of said grates and having a hopper section and a magazine section, the side walls of said sections being in alinement, said magazine section being unobstructed from end to end and said hopper section flaring upwardly from the hopper feed opening onward, and a feed screw operating in the bottom of the trough, said feed screw terminating well in advance of the rear end of the magazine and having its conveyer blades of substantially the same pitch throughout, the sides of said trough serving as coking surfaces for the coal before its delivery to the inclined grates; substantially as described. 75 80 85 90 95

In testimony whereof I affix my signature, in presence of two witnesses.

GEORGE H. THACHER, JR.
